UNITED STATES PATENT OFFICE.

ASA LYON, OF CHICAGO, ILLINOIS, ASSIGNOR TO THE ENVELOPE AND STAMP MACHINE COMPANY, OF SAME PLACE.

DESIGN FOR A CASE FOR VENDING-MACHINES.

SPECIFICATION forming part of Design No. 22,102, dated January 3, 1893.

Application filed November 5, 1892. Serial No. 451,122. Term of patent 14 years.

To all whom it may concern:

Be it known that I, ASA LYON, a citizen of the United States, residing at Chicago, in the county of Cook and State of Illinois, have invented and produced a new and original Design for Cases for Vending-Machines, of which the following is a specification, reference being had to the accompanying drawings, in which the figure is a perspective view.

- The leading feature of my design consists in a case substantially square, provided with a slightly flaring base and a dome shaped top

surmounted by an ornamental figure. On the corners of the body of the case are placed medallions bearing ornamental figures, and between the medallions are inscription spaces or openings.

I claim,—

The design for a case for vending machines, substantially as herein shown and described. 20
ASA LYON.
